CERAMIC TILE

Joseph Stephen Wheeler, Jr., 1/2 Huntington Tile, Inc.,
9223 Bolsa Ave., San Diego, Calif. 92683

Filed Feb. 17, 1967, Ser. No. 5,849

Term of patent 14 years

(Cl. D18—2)

FIG. 1 is a perspective view showing the top inner edge and one end edge of my new tile;

FIG. 2 is a perspective view showing the bottom inner edge and the other end edge of my new tile;

FIG. 3 is a top view of the tile that I provide;

FIG. 4 is a bottom view of my new design; and,

FIG. 5 is a view of one side of my new tile design.

I claim:

The ornamental design for a ceramic tile, as shown and described.
